Primary Examiner — Carol P Rademaker(74) *Attorney, Agent, or Firm* — Stephen Kenny; Peter Sullivan; Foley Hoag LLP(57) **CLAIM**

The ornamental design for a perfume bottle, as shown and described.

DESCRIPTION

FIG. 1 is a front elevational view of the invention;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a top, front, and right side perspective view thereof; and,

FIG. 8 is a top, front, and right side perspective view thereof, with the cap shown separately.

The logo "BVLGARI" depicted in certain figures merely represents written matter surface ornamentation which does not form any part of the claimed design.

1 Claim, 8 Drawing Sheets(56)
